UNITED STATES PATENT OFFICE.

WILLIAM POLLARD DIGBY, OF LONDON, ENGLAND.

MANUFACTURE OF HYPOCHLORITE SOLUTIONS BY ELECTROLYTIC METHODS.

No. 892,983.

Specification of Letters Patent.

Patented July 14, 1908.

Application filed September 18, 1906. Serial No. 335,140.

To all whom it may concern:

Be it known that I, WILLIAM POLLARD DIGBY, of 82 Victoria street, Westminster, in the county of London, England, consulting electrical engineer, have invented certain new and useful Improvements Relating to the Manufacture of Hypochlorite Solutions by Electrolytic Methods, of which the following is a specification.

10 This invention relates to the manufacture of solutions of hypochlorites of sodium, magnesium, or calcium by electrolytic methods from their respective chlorids.

15 In other electrolytic processes for the manufacture of hypochlorite solutions, the substances liberated at the anode and cathode are allowed to recombine in the main body of the solution which is being submitted to electrolysis, with the result that a complete decomposition of the chlorid within the electrolyte becomes an impossibility, and it is rarely that more than one-fourth of the chlorin initially present in the form of chlorid becomes converted into available chlorin 25 in the hypochlorite form.

Now according to the present invention I prevent the recombination of the products liberated at the anode and cathode from taking place in the main body of the electrolyte 30 and provide that this recombination shall take place in a compartment or compartments where one of the products is liberated in a nascent condition. By this means the waste of unconverted chlorid is prevented or 35 reduced, and the delivery of a liquid of any specified strength can be regulated by varying the inflow of liquor into the cathode cell.

According to my invention I may employ 40 a separate porous cell or suitable partition around both the anode and cathode plates disposed in the main body of the electrolyte which should have its saline constituents replenished from time to time. A very small space is left between the surface of the elec- 45 trode and the inner side of its cell. I feed into the cathode cells either pure water or water containing in solution an alkaline substance such for example as caustic soda or carbonate of soda. From the cathode cell 50 this liquor, much enriched by the alkaline products liberated at the cathode may be passed through a suitable cooling arrangement, and is led into the anode cell where it may pass along a zig-zag course over the sur- 55 face of the anode and between the anode and

its cell. Here it absorbs the chlorin gas liberated at the anode, the result being that the caustic alkali solution is decomposed therein to form a hypochlorite or oxychlorid of the alkali present, the resultant liquor being led 60 off for use. Inasmuch as considerable quantities of heat are liberated during the process of electrolysis, whereby the resultant product may be rendered unstable, especially in hot climates, the anode or cathode, or both, 65 may be made hollow and compressed gases such as ammonia may be allowed to expand therein. I find however that the cooling of the liquor on its passage from the cathode cell to the anode cell as above mentioned 70 may be dispensed with.

In the accompanying drawings, Figures 1, 2 and 3 illustrate by way of example a suitable form of apparatus embodying the invention and intended for working on a low voltage parallel system. Fig. 1 is an end elevation with the end of the tank removed. Fig. 2 is a similar view at right angles to Fig. 1 and in conjunction with the enlarged sectional detail Fig. 3 serves to show the construction of the casings or cells *e e*. Fig. 4 is a sectional plan illustrating a form of apparatus adopted for a series system of a higher voltage. Fig. 5 is a sectional plan of a modified form of apparatus. Fig. 6 is a 85 similar view illustrating an apparatus having a cooling means. Fig. 7 is a vertical section showing a construction having a covered top in which the gases are collected. Fig. 8 is a vertical section of an apparatus in which the 90 cells are horizontally arranged.

a is an iron tank coated inside with a preparation of bitumen.

b b are bars of wood or ebonite from which are suspended the cathodes *c c*, two of which 95 are shown with a central anode *d* by way of illustration. The cathodes *c c* may be of iron, copper or zinc. They have each a porous casing or cell *e* secured to them by ebonite bolts and distance pieces as shown, 100 these cells being closed at the bottom and sides. The wires *f f* carry the current from each cathode to the negative pole of the dynamo. The central anode *d* is of graphite and is fitted with similar casings or cells *e e* to 105 those fitted to the cathodes; the wire *g* carries the current from the positive pole of the dynamo.

h is an inlet pipe to admit fresh water or water containing caustic soda or carbonate 110

of soda in solution into each cathode compartment. The body of the electrolyte fills the tank and occupies the space between the respective cells. The sodium liberated in the 5 cathode compartments forms a solution of caustic soda which overflows through the pipes or connections i into the compartments between the anode d and its casings e . The chlorin gas liberated at the anode combines 10 in the compartments thereof with the alkaline liquor from the cathode to form a solution of hypochlorite, which is drawn off from the pipe j by a siphon or pump.

The preferred construction of the casings 15 or cells e is shown in Figs. 2 and 3. It comprises an outer casing of ebonite k or the like with slots cut vertically therein as seen in Fig. 2, next to this is placed a sheet of asbestos or other porous material k' and within 20 this another ebonite sheet k'' with slots cut horizontally therein as shown in dotted lines in Fig. 3, the whole being clamped together by the ebonite bolts k^5 , in Fig. 1 and held at a small distance from the electrode by the distance pieces. 25

It will be understood that the main electrolyte, for example sodium chlorid solution is decomposed by the electric current acting through the slots and porous material of the 30 electrodes, the sodium ions passing to the cathodes and the chlorin ions to the anode, the solution of caustic soda formed at the cathode passes by the connections i to the anode compartments and combines therein 35 with the chlorin to form sodium hypochlorid solution which is led away by the pipe j .

When pure water is fed into the cathode cells, it will be understood that it almost immediately takes up sodium ions which percolate 40 through the cathode cell walls, so that its conductivity is greatly increased.

Fig. 4 is a sectional plan illustrating a form 45 of apparatus for a series system of higher voltage. a is the tank and l an inlet pipe for the saline solution to be electrolyzed, which flows in a zig-zag manner around the electrodes m to the outlet pipe l' as shown by the arrows. In the tank a the right hand 50 electrode m is connected to the positive pole of the circuit and acts as an anode on its left face while the left hand electrode m is connected to the negative pole and acts as a cathode on its right face. The intermediate electrodes act as anodes on their left hand 55 sides and as cathodes on the right. Each of the anode and cathode faces is fitted with a cell or casing e similar to those described in the foregoing example and the anode and cathode compartments of each electrode 60 communicate by orifices n , while the adjacent compartments of successive electrodes are connected by short overflow pipes or connections o . The fresh water or soda solution is admitted to the extreme cathode 65 chamber at p and a liquid containing caus-

tic soda overflows through the connections o into the adjacent anode compartment, whence it flows through an orifice n into the adjacent cathode compartment and so on through the series of electrodes to the final 70 overflow outlet p' , becoming fed alternately with caustic soda in the cathode compartments and free chlorin in the anode compartments, and gaining in hypochlorite as each stage is passed. 75

In the apparatus illustrated the anodes and cathodes are shown solid but they may as explained be made hollow and connected to any known system for expanding ammonia or other compressed gas in their hollow interior. Such an arrangement will be understood without further explanation. Moreover baffles or obstructions may be provided in the anode and cathode compartments to cause the liquid to take a zig-zag 85 course over the surface of the electrodes. 80

For series working I do not confine myself to the method of circulation shown for the products of electrolysis. As an alternative, each cathode compartment may have its 90 separate fresh water inflow and caustic soda outflow into a common sump, whence the alkaline liquor may be pumped so as to flow from anode compartment to anode compartment, becoming enriched from stage to stage; 95 or the alkaline liquor obtained in the cathode cell or cells may be so distributed as to be led separately into each anode cell or compartment, each of which would have a separate outflow. Such an apparatus is illustrated in 100 Fig. 5, in which l is the inflow and l' the outflow of the saline solution to be electrolyzed. The electrodes m are arranged in a similar manner to that in Fig. 4 so that the electrolyte flows around them in a zig-zag 105 course to the outlet l' , and diaphragms e are fitted to the electrodes as before.

p^2 is a fresh water pipe with inlets p^3 each leading to a cathode compartment which are on the right faces of the respective electrodes. The liquid from the cathode compartments flows out by separate connections p^4 and a pipe p^5 to the sump s whence the cathode liquor is pumped by the pump r through the pipe t into the right hand anode 115 compartment and traverses the anode compartment in succession by the overflow pipes o' , finally outflowing through pipe o^2 .

For series working, all the electrodes will 120 preferably be of graphite and would be arranged as shown in Fig. 4, or a number of tanks, each separately designed for parallel working might be joined in series.

When it is desired to cool the liquor on its 125 passage from the cathode compartment to the anode compartment, this can be done by leading it through a tubular or other cooler before allowing it to enter the anode compartment instead of leading it from cathode to anode compartment by overflow or other 130

direct connections as illustrated. Such a construction is shown in Fig. 6. The arrangement of the electrodes in this figure is similar to that in Fig. 5 and the saline solution flows round them in the same way being admitted at l and flowing out at l' . Fresh water is admitted to the end cathode compartment by the pipe p^6 and overflows through the cathode compartment in succession by the pipes p^7 and thence passes by the pipe p^8 to the sump s , whence the pump r forces the cathode liquor through the cooling coil v and pipe q to the separate anode compartments by branches q' . The outflow of the hypochlorite solution from these compartments runs away by the branches q^2 and pipe q^3 .

In place of carrying the liquor from the cathode cell or cells to the anode cell or cells the porous partition of the latter may be made with a covered top fitted with a pipe arranged to lead the gases evolved away to a small air pump which delivers the chlorin gas through small apertures at the base of the cathode compartment wherein it unites with the alkaline liquor to form a hypochlorite. Fig. 7 shows such a construction. The arrangement of the electrodes and diaphragms is similar to that shown in Fig. 1, but the connections are different. The main saline electrolyte is contained in or circulated through the tank. The anode and cathode compartments are not connected together but a bell shaped cover w is fitted over the anode. In this cover the chlorin gas is collected and is sucked away by the pump x which delivers it through the pipe x' to the bottom of each cathode compartment. The outflow of the hypochlorite liquor from the cathode compartments is shown at j' .

Alternatively in place of the arrangement of vertical electrodes shown and described, the principle of my invention might in the case of parallel working or of single tanks in series be applied to a tank or tanks in which the electrodes are fitted horizontally. In the latter event a mercury cathode may be employed and the cathode cell or diaphragm dispensed with. In this case the sodium or corresponding metal liberated at the cathode combines with the mercury in the known way and is thus isolated, prevented or largely prevented from being taken up by the main electrolyte, the amalgam formed at the cathode being led into a separate chamber and washed with water in the known manner; the resulting caustic soda or corresponding alkaline solution is then pumped or supplied between the anode or anodes and the porous cell or cells thereof. The anode or anodes may be suspended above the mercury cathode in the known way. Fig. 8 shows in vertical section an arrangement such as just referred to. In this case the electrode m is disposed horizontally in the tank a . The sa-

line solution to be electrolyzed is admitted at l and flows out at l' . The anode is fitted with a diaphragm e . The cathode is formed by a layer of mercury m' with which the tank is kept supplied; no diaphragm is required in this case, as the mercury itself acts as the isolator for the liberated sodium, which it at once takes up and thus keeps separate from the chlorin evolved at the anode. From the tank a the mercury sodium amalgam passes by the pipe l and is sprayed by the heat 2 into a tank 3 through which a circulation of water is maintained. The resulting caustic solution is pumped from the tank 3 and delivered by the pipe 4 to the anode compartment 4 where it takes up the chlorin evolved, the resulting hypochlorite solution flowing away at 5 . The mercury regenerated in the tank 3 is pumped back to the tank a by the pump 6 .

These various modifications of arrangement and detail will be readily applied by practical men from the description above given, it being understood that while the union of the anode and cathode products may be effected in either the anode or in the cathode compartment, the essential feature of this invention lies in the fact that the recombination of the products does not take place in the main body of the electrolyte, but in the compartment where one of the products is liberated in a nascent condition.

What I claim and desire to secure by Letters Patent is:—

1. In the electrolytic production of hypochlorite solutions, isolating or shielding from the main body of electrolyte the decomposition products liberated at the anode and cathode and conveying one of said products from the electrode at which it is liberated into a cell or compartment closely adjacent to an electrode of opposite sign and shielded from the main body of electrolyte by a porous partition, substantially as and for the purpose specified.

2. In the electrolytic production of hypochlorite solutions, shielding the electrodes from the main body of electrolyte by porous partitions disposed in proximity to their respective electrodes and forming porous cells therefor, feeding a separate aqueous liquid through a cathode cell and thence conducting it out of contact with the main body of electrolyte through an anode cell so that said liquid passes through cells of opposite sign substantially as and for the purposes described.

3. In the electrolytic production of hypochlorite solutions, shielding an anode and a cathode from the main body of electrolyte by porous partitions disposed in proximity to their respective electrodes and forming porous cells therefor connected by a conduit, feeding a separate aqueous liquid through the cathode cell and thence conducting it by

- said conduit into the anode cell, so that said liquid passes through both cells, substantially as and for the purposes described.
4. In the electrolytic production of hypochlorite solutions, shielding a plurality of anodes and cathodes from the main body of electrolyte by porous partitions disposed in proximity to their respective electrodes and forming porous cells therefor, the cathode cells being connected to the anode cells, by conduits, and circulating a separate aqueous liquid through the cathode cells and anode cells and their connecting conduits substantially as and for the purposes described.
- 10 5. In the electrolytic manufacture of hypochlorite solutions, shielding an anode from the main body of electrolyte by a porous partition disposed in proximity to said anode and forming a porous cell therefor, electrolyzing the main electrolyte by the said anode and a mercury cathode, washing the resulting amalgam to form an alkaline solution and feeding said solution into the said anode cell out of contact with the main electrolyte.
- 20 6. In the electrolytic production of hypochlorite solutions bringing a decomposition product into contact at an electrode of opposite sign with the nascent decomposition

product liberated at said electrode of opposite sign, while shielding both products from the main body of electrolyte.

7. In the electrolytic production of hypochlorite solutions, inclosing from the main body of electrolyte the decomposition products liberated at the electrodes, conducting one of said products, out of contact with the main body of electrolyte to an electrode at which the other product is liberated in the nascent condition substantially as described.

8. In the electrolytic production of hypochlorite solutions, inclosing from the main body of electrolyte the decomposition products liberated at the electrodes, conducting one of said products, out of contact with the main body of electrolyte, to an electrode at which the other product is liberated in the nascent condition and cooling the electrodes by expanding a compressed gas therein, substantially as described.

In witness whereof, I have hereunto signed my name in the presence of two subscribing witnesses.

WILLIAM POLLARD DIGBY.
